[57] **CLAIM**

The ornamental design for a holder (with sleeve) for interproximal brushes, as shown.

DESCRIPTION

FIG. 1 is a side elevation view of the interproximal brush holder for supporting a replaceable brush on one end and a toothpick on the other end;

FIG. 2 is an elevation view of the bottom of the interproximal brush holder taken in the plane 2—2 of FIG. 1;

FIG. 3 is an elevation view of the top of the interproximal brush holder taken in the plane 3—3 of FIG. 1;

FIG. 4 is an end view of the interproximal brush holder taken in the plane 4—4 of FIG. 3;

FIG. 5 is an end view of the interproximal brush holder taken in the plane 5—5 of FIG. 3;

FIG. 6 is a side elevation view of the upper end of the interproximal brush holder of FIG. 1 with sleeve in place; and

FIG. 7 is a side elevation view of the lower end of the interproximal brush holder with a sleeve in place thereon.

FIG. 2

FIG. 1

FIG. 3
